UNITED STATES PATENT OFFICE.

NELSON P. RIDGWAY, OF TACOMA, WASHINGTON.

ROTARY HAMMER.

1,216,166.

Specification of Letters Patent. Patented Feb. 13, 1917.

Application filed October 18, 1915. Serial No. 56,633.

To all whom it may concern:

Be it known that I, NELSON P. RIDGWAY, a citizen of the United States, residing at Tacoma, in the county of Pierce and State of Washington, have invented a new and useful Improvement in Rotary Hammers, of which the following is a specification.

This invention relates to improvements in rotary hammers, and the object of the improvement is to provide a strong, simple and efficient device of this class that is adapted when it is rotated to strike blows in rapid succession.

The invention consists in the novel construction, adaptation and combination of parts as will be more fully described in the following specification, illustrated in the accompanying drawings and finally pointed out in the appended claims.

20 In the accompanying drawings Figure 1 is a view in vertical section of a rotary hammer embodying my invention; Fig. 2 is a view in cross section on broken line 2, 2 of Fig. 1; Fig. 3 is a fragmentary view in cross section illustrating an operative position of a hammer element; Fig. 4 is a fragmentary sectional view on broken line 4, 4 of Fig. 1 and Fig. 5 is another fragmentary sectional view on broken line 5, 5 of Fig. 1.

30 Referring to the accompanying drawings throughout which like reference numerals indicate like parts, the numeral 6 indicates a circular casing that is provided on one side with a handle 7 of any convenient form and on another side with a hollow extension 8 within which is slidably disposed the shank 9 of a riveting tool or other instrument that is adapted to be struck a plurality of blows in rapid succession.

40 Concentrically disposed within the casing 6 and adapted to rotate on a shaft 10 is a hammer body 11 that is provided with one or more hammer elements 12 as clearly shown in Fig. 1 and is adapted to be rotated by an induction motor consisting in a stationary armature 13 that is secured to the casing 6 and a rotating field 14 that is secured to the hammer body 11 as illustrated diagrammatically in Figs. 1 and 2, the motor being connected by electric circuit wires 15 with a source of supply of electrical current, (not shown).

55 The hammer elements 12 are slidably mounted within holders 16 that are secured to the hammer body 11 in any suitable manner as by screws 17 and such hammer ele-

ments are adapted to work against rollers 18 that are disposed with their ends in slots 20 in the holders 16 whereby the hammers may slide more easily within the holders. 60

The hammer elements 12 are limited in their outward movement by stops 21, formed integral with the sides 16 of the holders 16, as more clearly illustrated in Figs. 4 and 5, to prevent such elements 12 from coming in contact with the casing 6. 65

In operation the device is set up as shown in Fig. 1 and electrical current is supplied to the motor to rotate the hammer in the direction indicated by the arrow A. 70

The radial lines of the hammer body 11 that pass through the centers of gravity of the hammer elements 12 are always inclined with respect to the direction of movement of the elements 12 within the guides 16, hence 75 when the device is rotated in the direction indicated by the arrow A centrifugal force acting outwardly on such radial lines will cause the hammer element to press against the inclined surface formed by the rollers 18 80 and such elements will be constantly held outward into the position shown in Fig. 1.

As the hammer body 11 rotates the hammer elements 12 will be moved by centrifugal force to the limit of their outward movement and each time they pass the end of the tool 9 will strike a blow thereon. When the hammer element 12 strikes the tool 9 the tool will be driven outward by the impact of the blow and the hammer will be moved 90 back into the casing 16 as shown in Fig. 3, the air in the rear of such casing serving as a cushion to prevent the rear end of the hammer from battering the rear end wall of the casing. As soon as the element 12 is 95 released by the tool 9 centrifugal force will cause it to again move outward into the position shown in Fig. 1.

The rollers 18 facilitate the movement of the hammer elements 12 and insure that such 100 elements will not bind on the walls of the guides 16 although it has been found in practice that such rollers are not necessary.

Having described my invention what I claim is:

1. A device of the class described comprising a casing, a body member mounted therein and having tangential guideways, a tool provided in said casing and hammer elements slidably mounted in said guideways said hammer elements being adapted to be held outward by centrifugal force into

a position to strike a blow on said tool when said body member is rotated.

2. A device of the class described, comprising a rotatable body member, a guide associated with said body member, rollers provided in said guide, a hammer element movable longitudinally in said guide and means associated with said guide for limiting the outward movement of said hammer element.

10 3. A device of the class described, comprising a casing having a tool mounted therein, a rotatable body member, a guide associated with said body member, and a hammer element movable in said guide in a direction that is inclined to the plane of the radial line joining the center of rotation of said body member and the center of gravity of said hammer element, whereby when said body member is rotated in one direction said hammer element will be held at the limit of its outward movement.

4. A device of the class described comprising a casing, a body member mounted for rotation therein, a tool, means for rotat-
25 ing said body member, guide members associated with said body member, hammer elements movable in said guide members in a direction that is inclined to the direction of the radial lines joining the center of rotation of said body member and the centers of gravity of said hammer elements whereby when said body member is rotated said ham-

mer elements will be moved outwardly, and means for limiting the movement of said hammer elements within said guides.

5. A hammer of the class described, comprising a casing, a body member mounted for rotation within said casing, a tool holding extension on said casing, a tool slidable in said tool holding extension, and adapted to project an end within close proximity of said body member, guides tangentially associated with said body member, and hammer elements slidably mounted within said guides and adapted to deliver a succession of blows on the end of said tool when said body member is rotated.

6. A portable self contained hammer comprising a circular casing, a tool slidably mounted therein, an annular body member mounted for rotation within said casing, a motor disposed within said body member, guideways provided in said body member substantially in tangential relation thereto, roller bearings in said guideways, hammer elements movable in said guideways and operable on said tool, and stops on said guideways for said hammer elements.

Signed by me at Tacoma, Washington,
this 25th day of Aug., 1915.

NELSON P. RIDGWAY.
